UNITED STATES PATENT OFFICE.

FELIX TWOREK, OF DUNCAN, NEBRASKA.

DEMOUNTABLE RIM.

Application filed December 11, 1923. Serial No. 679,875.

To all whom it may concern.

Be it known that I, FELIX TWOREK, a citizen of United States, residing at Duncan, in the county of Platte and State of Nebraska, have invented certain new and useful Improvements in Demountable Rims, of which the following is a specification.

This invention relates to improvements in demountable rims for vehicle wheels and has as one of its objects to provide a device which may be permanently attached to the rim or the like and by which the rim ends may be held in normal operative position or forced apart to permit dismounting.

Another purpose is to produce a device which is entirely self-contained, requires the use of no tools or accessories in its operation and which occupies a limited space not otherwise utilized.

A further aim is in the provision of a simple and effective device for clamping or releasing a rim, comprised of few parts, cheaply made and easy to apply.

These several aims and objects are accomplished by the novel construction and arrangement of parts hereafter described and shown in the accompanying drawing, forming an essential part of this disclosure, and in which:—

Figure 1 is a fragmentary longitudinal sectional view showing a conventional type of wheel rim at its joint and illustrating the application of the invention, the same being shown as in a closed or clamping position.

Figure 2 is a side elevational view of the same, but showing the rim as separated and the device as in operative position.

Figure 3 is a fragmentary plan view looking from the inner side of the rim.

Referring to the drawing more in detail, the numeral 10 designates the web or body portion of a conventional form of split rim of the clincher type having raised peripheral flanged edges 11, the rim ends having a single abutting joint in which the end edges 12 and 13 are formed at an angle as shown, but it is to be understood that the device is applicable to other type of rims as well.

A hinge element 14 is secured by rivets 15

or like securing means to the inner surface 50 of the rim web 10 at a point near the joint and connected by a pivot pin 16 to the element 14 is a lever 17 curved to the radius of the rim and having a relatively wide finger grip 18 of reduced thickness at the 55 free outer end.

Said lever 17 contains two openings respectively 19 and 20 midway in its length, the first opening 19 being receptive of a flat bent spring detent 21 held in rigid relation to the web 10 by a clamp block 22 adapted to be received in the opening 20, serving to guide the lever 17 and preventing accidental lateral displacement.

A pair of blocks 23 are held by rivets 24 65 to the web 10 and are spaced to receive between them the lever 17 at a point near the handle element 18.

Pivoted in these blocks are rods 25, curved to suit the inner side of the web 10, the 70 free ends being engaged by a pin 26 passing transversely through the lever 17 at a point relatively near the joint 12—13.

In addition to the foregoing a strong wire loop 27 is pivoted in a pair of brackets 28 75 fixed on the rim portion bearing the element 14, this loop providing means for securing the rim end while operating on the other, serving as an anchor.

In operation, when the rim is to be contracted, as in applying a tire, the lever is released from the detent or catch 21 and drawn by hands toward the loop, which at that time may be engaged with some fixed object; this movement of the lever draws the rod 25 in a circular path of which the pin 16 is the axis, moving the end 12 of the rim over and past the end 13, thus decreasing the diameter of the rim permitting changes to be made in the tire.

Obviously, pressing the lever into position shown in Figure 1 causes the parts to assume their normal holding position.

From the foregoing it will be seen that a novel and practical device for the purpose 95 has been disclosed, but clearly minor changes may be made without departing from the spirit of the invention as hereafter claimed.

Having thus described my invention, what I claim as new and desire to secure by Letters Patent, is:—

A rim having abutting ends adapted to form a joint, a lever hinged to said rim adjacent one end thereof to extend past the joint, a pair of blocks fixed in spaced relation on the other end of said rim, pivoted

arms connecting said lever and blocks, said blocks acting to guide said lever, a central 10 guide for the lever, and a spring clip normally holding said lever in close proximity with the rim.

In witness whereof I have affixed my signature.

FELIX TWOREK.
